(57) **CLAIM**

The ornamental design for an ABNH hidden image reader, as shown and described.

DESCRIPTION

FIG. 1 is an isometric view of the design for an ABNH hidden image reader.

FIG. 2 is a second isometric view thereof;

FIG. 3 is a third isometric view thereof; and,

FIG. 4 is a fourth isometric view thereof.

The elements rendered in broken line are for illustrative purposes only and form no part of the claimed design.
